United States Patent Office

Des. 231,355

Patented Apr. 16, 1974

231,355

FAN

Georg Papst, St. Georgen, Black Forest, Germany, assignor to Papst Motoren, K.G., St. Georgen, Black Forest, Germany

Filed Dec. 22, 1971, Ser. No. 211,146

Term of patent 14 years

Int. Cl. D23—04

U.S. Cl. D23—160

Fig. 1

Fig. 2

FIG. 1 is a perspective view from the top and one side of a fan showing my new design;

FIG. 2 is a top plan view thereof;

FIG. 3 is a bottom plan view thereof;

FIG. 4 is a side elevation view thereof; and

FIG. 5 is an end view thereof.

I claim:

The ornamental design for a fan, substantially as shown and described.
